UNITED STATES PATENT OFFICE.

AARON H. GILL, OF WEST HAVEN, CONNECTICUT.

TOY ELECTRIC-RAILWAY CONTROL DEVICE.

Application filed July 14, 1926. Serial No. 122,355.

Fig. 1 is a schematic plan view of a toy electric-railway control-system constructed in accordance with my invention;

Fig. 2 is a view in front elevation of the electrically-operated semaphore signal tower, the train-control switch thereof being shown in its circuit-closing position;

Fig. 3 is a view in edge elevation of the ramp-switch;

Fig. 4 is a top or plan view thereof; and

Fig. 5 is a transverse sectional view on the line 5—5 of Fig. 4 and, in addition, indicating the contact-shoe of an electric engine by broken lines.

This invention relates to an improvement in toys, and particularly toy electric-railway control-devices. The object of this invention is to provide a control-device by means of which one toy train may be automatically stopped or started by the movement of another train past a given point.

My invention consists in a toy electric-railway control-system having certain details of construction and combinations of parts as will be hereinafter described and particularly recited in the claims.

In the embodiment of my invention herein shown, the usual three-rail track is employed, consisting of outside rails 10—10 and a "third" or power rail 11, arranged in the form of a return loop. Preferably, the rails 10—10 are connected to the negative side of the source of electrical energy, such as a battery 12, while the rail 11 is connected to the positive side thereof.

At any suitable point I insert in the track a section having a third rail 13 insulated from the main third rail 11 and connected by wires 14 and 14^a to one contact 15 of a train-control switch 16, the complementary contact 17 of which is connected to the positive side of the battery 12 by means of wires 18 and 18^a. The contacts 15 and 17 are adapted to be electrically connected by means of a metal ring 19 insulated from and carried by a semaphore-operating rod 20, which is connected at its upper end to an oscillating semaphore-arm 21 pivoted, as at 22, to a vertical standard 23 projecting upward from a base 24. At its lower end the semaphore-operating rod 20 carries an armature 25 moving axially within a circuit-closing solenoid 26 and a circuit breaking solenoid 27. One terminal of each of the solenoids 26 and 27 is connected by wires 28 and 28^a to the negative side of the battery 12,

For the purpose of energizing the solenoids 26 and 27 and thus operating the semaphore 21 and train-control switch 16 as required, I employ what I shall, for convenience, designate as ramp-switches 29 and 30, located between the rails 10 and over the third rail 11, the ramp-switch 29 being connected by wires 31 and 31^a to the circuit-closing solenoid 26, while the ramp-switch 30 is connected to the circuit-breaking solenoid 27 by wires 32 and 32^a.

Each of the corresponding ramp-switches 29 and 30 consists of a frame-plate 33 carrying on opposite sides of its longitudinal center two bars 34 and 35 of insulating material. Between these two bars the frame-plate 33 is folded to form a longitudinal channel 36 adapting the ramp-switch as a whole to be set between the rails 10—10 and over the third rail 11, as clearly shown in Fig. 5. Integral or connected with the frame-plate 33 is a contact-strip 37 located on top of the bar 35. Similarly located on the bar 34 is a complementary contact-strip 38 provided at one end with a binding-post 39 to which circuit-wires may be attached. As thus constructed, the ramp-switches are adapted to have the contact-shoe 40 of the toy electric engine (shown by broken lines in Fig. 5) close the electric gap between the contact-strips 37 and 38 as the engine passes over the ramp-switch, and thus closes the circuit through either of the solenoids 26 or 27, depending upon which of the two ramp-switches 29 and 30 is engaged by the engine contact-shoe.

Having fully described the nature of my invention, I shall now proceed to describe its mode of operation.

For convenience of description, it may be presumed that there are two toy trains operating on the track-system shown in Fig. 1, and that the track-switch is appropriately set to permit a train to travel in the direction indicated by the arrows, and that one engine A is at rest with its contact-shoe 40 in engagement with the insulating third rail section 13, which at this time is uncharged, owing to the fact that the train-control switch 16 is in its circuit-breaking position, and further that a second engine B is moving as indicated by the arrows.

As the electric engine B passes over the ramp-switch 29, its shoe 40 will close the circuit between the contact-strips 37 and 38 thereof, and thus cause a current to flow

from the third rail 11 through the wires 31^a and 31, thence through the circuit-closing solenoid 26, wires 28 and 28^a, whereby the said solenoid 26 is energized, with the effect 5 of lifting the armature 25 and hence throwing the semaphore-arm 21 into its depressed position and bringing the ring 19 in position to connect the complementary contacts 15 and 17 and thus complete a circuit from 10 the battery 12 to the third rail section 13, which will now become energized and cause the electric train A stalled thereover to start up and move out of the looped part of the rail system. As this train A moves forward 15 its shoe 40 will bridge the gap between the contact-strips 37 and 38 of the ramp-switch 30, thus causing a current to flow from the third rail 11 through wires 32^a, 32, circuit-opening solenoid 27, wires 28 and 28^a, with 20 the effect of energizing the said circuit-opening solenoid 27. This will result in a downward draft upon the armature 25 and cause the semaphore-arm 21 to move into its danger-indicating position and, at the same 25 time, cause the ring 19 of the train-control switch 16 to move out of engagement with the complementary contacts 15 and 17, and thus break the circuit therethrough. The 30 breaking of the circuit as just described will de-energize the third-rail section 13, whereby, when the engine B reaches the said third-rail section now de-energized, it will fail to receive any current and hence come to a stop over it. The train B will remain at rest 35 until another engine again passes over the ramp-switch 29, so as to cause the third-rail section 13 to again be energized.

It will be understood that the number and relative positions of the ramp-switches may 40 be varied and that the track arrangement forms no part of my invention.

It will also be understood that by the use 45 of the term "solenoid" herein I wish to include all variations of electro-magnets.

I claim:

1. A toy electric-railway control-device, comprising a visual indicating-signal; a standard therefor; a solenoid for moving said signal into its danger-indicating position; a 50 second solenoid for moving the said signal into its clear-track-indicating position and arranged axially in line with the first-mentioned solenoid; an armature axially ar-

ranged within and extending between both of said solenoids; a signal-operating rod 55 axially in line with and forming an extension of said armature; a movable switch-member connected to the said armature for operation thereby; and a complementary stationary switch-member carried by the said standard; whereby a train-control circuit may be made or broken concurrently with the operation of said visual indicating-signal.

2. A toy electric-railway control-device, comprising a pivotal semaphore-arm; a 60 standard therefor; a solenoid for moving said semaphore-arm into its danger-indicating position; a second solenoid for moving the said semaphore-arm into its clear-track indicating position and arranged axially in 65 line with the first-mentioned solenoid; an armature axially arranged within and extending between both of said solenoids; a semaphore-operating rod axially in line with and forming extension of said armature; a 70 movable switch-member connected to the said armature for operation thereby; and a complementary stationary switch-member carried by the said standard; whereby a train-control circuit may be made or broken 75 concurrently with the operation of the said semaphore-arm.

3. A toy electric-railway control-device, comprising a visual indicating-signal; a standard therefor; a solenoid for moving 80 said signal into its danger-indicating position; a second solenoid for moving the said signal into its clear-track-indicating position and arranged axially in line with the first-mentioned solenoid; an armature axially arranged within and extending between both of said solenoids; a signal-operating rod axially in line with and forming an extension of said armature; a stationary switch-member carried by said standard; a movable 85 switch-member having sliding engagement with the said stationary switch-member and arranged axially in line with and connected to the said armature for operation thereby; whereby a train-control circuit may be made 90 or broken concurrently with the operation of said visual indicating-signal.

In testimony whereof, I have signed this specification.

AARON H. GILL.
